ORNAMENT FOR DOOR STOOPS

Marshall F. Clay, Canton, Ohio

Application September 3, 1949, Serial No. 4,847

Term of patent 7 years

(Cl. D13—2)

To all whom it may concern:

Be it known that I, Marshall F. Clay, a citizen of the United States, residing at Canton, in the county of Stark and State of Ohio, have invented a new, original, and ornamental Design for Ornament for Door Stoops, of which the following is a specification, reference being had to the accompanying drawing, forming a part hereof.

Figure 1 is a side elevation of an ornament for door stoops, showing my new design, and

Fig. 2 is a top plan view of the ornament for door stoops shown in Fig. 1.

I claim:

The ornamental design for an ornament for door stoops, substantially as shown.

MARSHALL F. CLAY.
